David F. Taylor Inventor

UNITED STATES PATENT OFFICE.

DAVID F. TAYLOR, OF WICHITA, KANSAS.

FLUE-THIMBLE.

SPECIFICATION forming part of Letters Patent No. 550,115, dated November 19, 1895.

Application filed December 11, 1894. Serial No. 531,505. (No model.)

To all whom it may concern:

Be it known that I, DAVID F. TAYLOR, a citizen of the United States of America, residing at Wichita, in the county of Sedgwick and State of Kansas, have invented certain new and useful Improvements in Flue-Thimbles, of which the following is a specification, reference being had therein to the accompanying drawings, and the letters of reference thereon, forming a part of this specification, in which—

Figure 1 is a perspective view of the flue-thimble; Fig. 2, a sectional elevation thereof, represented as set in a flue, also showing a pipe placed therein; Fig. 3, a perspective view of the thimble-stopper, and Fig. 4 a front view representing the stopper placed in the flue.

The invention relates to flue-thimbles; and it consists in the particular means which I employ to hold the stovepipe in place.

B represents the thimble, which has fitted thereon a collar C, a little distance back from its forward end, thereby leaving a flange portion, as shown at R, extending beyond said collar. The rear end of said thimble is made with a series of longitudinal slits, as represented at V.

The extending flange R is made with a segmental slot F, and secured to said flange adjacent said slot is a spring S' of bowed form, which overreaches said slot and terminates in a clamping foot-piece S, which is by means of the spring portion yieldingly held extended through said slot toward the center of the thimble, and as a means of conveniently operating said foot-piece S it is provided with a knob G, which is made to be grasped by the

fingers of a person, so the said foot-piece may be lifted from the slot by yielding back the spring S'.

In service the thimble is placed in a flue, placing the slotted end foremost, bringing the collar to register with the wall about the flue (see Fig. 2) and bringing the slotted end through the flue, when the end sections made by said slitting are bent radially against the wall adjacent the inner end of the flue, and by so doing the thimble is secured in the flue, subject, however, to removal therefrom by straightening said end sections.

When the thimble is thus placed either a stopper (shown at D) having a flange D' and knob Z may be placed with the flange D' into the thimble to close it, which is done by first lifting the spring-foot S', or a pipe, such as a stovepipe, may be placed in like manner, as represented at P in Fig. 2, and in either instance when the spring-foot S is released it comes in contact with and yieldingly but firmly bears against the stopper-flange D' or pipe P, thereby holding them firmly sealed.

Having thus described my invention, what I claim as new and useful, and desire to secure by Letters Patent, is as follows:

A flue thimble having the outer slot F in combination with a plate spring provided with the clamping foot S and held by its tension within said slot, to grip a stopper or pipe passing therewith as and for the purpose set forth.

DAVID F. TAYLOR.
